UNITED STATES PATENT OFFICE.

MAURICE R. ROSEN AND RUDOLPH E. FISCHEL, OF CHICAGO, ILLINOIS.

AUTOMOBILE-LOCK.

1,266,161.

Specification of Letters Patent.

Patented May 14, 1918.

Application filed October 1, 1917. Serial No. 194,168.

To all whom it may concern:

Be it known that we, MAURICE R. ROSEN and RUDOLPH E. FISCHEL, citizens of the United States, residing at Chicago, in the county of Cook and State of Illinois, have invented a new and useful Improvement in Automobile-Locks, of which the following is a specification.

This invention relates particularly to means adapted to prevent the theft of automobiles; and the primary object is to provide an improved steering-wheel and lock equipment adapted to secure the steering-wheel in inoperative condition, when desired.

The invention is illustrated in its preferred embodiment in the accompanying drawings, in which—

Figure 1 represents a broken side elevational view of a steering-column equipped with the improved steering-wheel and lock equipment; Fig. 2, a broken plan view of the same; Fig. 3, an enlarged broken sectional view, taken as indicated at line 3 of Fig. 2, and showing the steering-wheel in inoperative condition; Fig. 4, a broken sectional view similar to Fig. 3, but showing the steering-wheel in operative condition, that is, locked to the steering-shaft; Fig. 5, a plan sectional view taken as indicated at line 5 of Fig. 3; Fig. 6, a broken plan sectional view taken as indicated at line 6 of Fig. 3; and Fig. 7, a sectional view of the lock-chamber, showing the lock therein, partly in section.

In the illustration given, A represents the tubular stationary steering column of a well known automobile, which is equipped with a cap A¹, in which is journaled the steering-shaft A²; and B, the improved steering-wheel and lock mounted upon the upper end of the shaft A².

The shaft A² is equipped, as is usual in this make of machine, with a pinion 1, through which motion is communicated in the usual manner to the shaft-section (not shown), which actuates the steering-knuckles (not shown) of the automobile.

The shaft A², the pinion 1, and the cap A¹ constitute a part of the regular equipment of an automobile of the make referred to.

In practice, the cap A¹ is firmly secured to the upper end of the stationary tubular

column A, as by screw connection. The cap 55 is equipped at its upper side with a reduced sleeve portion 2, in which is journaled an enlarged portion 3 of the shaft A². Above the enlarged portion 3 the shaft has a portion 3^a of smaller diameter than the portion 60 3, and extending upwardly from the portion 3^a is a reduced threaded portion 3^b, which receives a nut 4.

Firmly secured on the portion 3^a of the shaft is a journal-collar B¹, which is provided circumferentially with a series of sockets 5.

The journal-collar 5 is preferably secured upon the upper extremity of the shaft A² by means of a key 6 and the nut 4, said 70 journal-collar having an internal shoulder 7, which rests upon the upper end of the enlargement or integral collar 3 of the shaft A². The shoulder at the upper end of the portion 3 is substantially flush with the 75 upper end of the sleeve 2, but preferably projects sufficiently above the sleeve 2 to enable the member B¹ to be clamped between the shoulder on the shaft and the nut 4. The journal-collar B¹ is further provided, 80 preferably, with a sleeve-portion 8, which freely encircles the upper portion of the sleeve 2.

The steering-wheel has an enlarged hub-portion B² and a lock B³, the chamber of 85 which is formed integrally with the hub-portion B² and one of the spokes of the steering-wheel.

In the illustration given, the steering-wheel is provided with four arms or spokes 90 9, which radiate from an intermediate portion of the hub B² and have their outer ends curved downwardly and connected with the circle 10 of the steering-wheel. The spokes and the lock are thus disposed above the 95 plane of the circle or rim of the wheel, so that the lock is readily accessible.

The hub B² is somewhat in the form of a cap, having a sleeve-portion 11, which is journaled on the journal-collar B¹ and has 100 a dome-portion 11^a, which houses the nut 4 and the upper end of the journal-collar B¹.

One of the arms 9 of the steering-wheel is specially formed to provide the chamber for the lock B³. This particular arm of the 105 wheel is made tubular, thus providing a bore 12, in which is reciprocably mounted a locking-bolt 13, whose inner end is adapted

2
to enter any one of the sockets 5 with which the journal-collar B¹ is provided. The tubular arm 9 has formed integrally therewith a tubular boss 14, in which is secured a lock-casing 15 of a lock. Said lock is provided with a rotatable, key-actuated barrel 16, which is adapted to be locked in a position corresponding with the retracted position of the bolt 13 by means of the usual tumblers 17 (one shown), with which the lock is provided. The lock-casing 15 is held in position in its chamber by means of a pin 18. The lock-casing is so secured that the barrel 16 is eccentrically positioned, or positioned somewhat below the center of the locking-bolt or plunger 13. The rear end of the key-barrel 16 is provided with a rectangular extension 16^a, which has firmly secured thereon a bolt-actuating disk or 20 cam 19.

The locking-bolt or plunger 13 has a reduced intermediate portion 13^a, thus providing a longitudinal recess 13^b in the bolt 13, which accommodates the actuating disk 19. The disk 19 is additionally secured to 25 the key-barrel by rivets or screws 19^a. The actuating member 19 is of somewhat elliptical shape, being provided at one edge with an arm 19^b.

30 When the bolt 13 is in the engaging position, the arm 19^b rests upon the shoulder afforded by the lower wall of the bore 12, as will be understood from Fig. 4. The member 19 is essentially eccentrically positioned with reference to the barrel 16, and is confined between the shoulders afforded by the bolt at the ends of the reduced intermediate portion 13^a. Thus, the member 19 is adapted to hold the bolt 13 either in the 35 operative position or in the retracted position; and it will be understood that the bolt may be positively retracted or projected by turning the key-barrel through the medium of a suitable key (not shown).

40 It is preferred to provide a substantial coil-spring 20, which aids in holding the bolt 13 in the operative position, that is, in the position connecting the steering-wheel to the shaft. This spring is inserted in the 45 bore 12, between the outer end of the bolt 13 and a plug 21, which is secured in the bore 12 by means of a pin 22. The key may, if desired, remain in the lock when the bolt 13 is in the operative position shown in 50 Fig. 4; and by means of the key the barrel 16 may be rotated to retract the bolt 13 against the force of the spring 20, to the 55 position shown in Fig. 3, whereupon the tumblers 17 will lock the barrel 16 in a position corresponding with the retracted position of the bolt 13. The key may then be 60 withdrawn, leaving the steering-wheel secured in inoperative condition upon the steering-shaft.

65 To equip a machine of the character re-

ferred to against loss by theft, it is only necessary to remove the ordinary steering-wheel, apply the journal-collar B¹ to the upper extremity of the steering-shaft; and then apply the steering-wheel equipped with 70 the locking mechanism, as illustrated. The steering-wheel is preferably secured rotatively to the journal-sleeve B¹ by means of a pin 23, which extends into the hub-portion B² of the wheel and engages an annular 75 groove 23^a with which the upper portion of the member B¹ is provided (Fig. 6).

From the description given, it will be understood that our invention provides a substitute steering-wheel equipped with 80 locking mechanism, which can be readily applied to the steering-shaft of an automobile; that by means of this improvement, the steering-wheel may be effectively locked in inoperative or disconnected condition; 85 and that when desired, the steering-wheel may be securely locked to the steering-shaft, thus enabling the vehicle to be steered as usual. If desired, the construction described may be adopted in the regular manufacture 90 of the automobile. However, when the automobile is equipped with the usual fixedly mounted steering-wheel, such steering-wheel may be removed and the improved device applied by supplying the improved steering- 95 wheel provided with the lock and the associated journal-collar B¹.

As has been explained, the central portion of the spider of the steering-wheel, which comprises the cap-shaped hub B² and the 100 radial arms formed integrally therewith, is disposed above the plane of the rim 10 of the steering-wheel. This contributes to the accessibility of the lock; and, as will be understood from Figs. 1 and 2, the whole 105 device presents a neat appearance.

The foregoing detailed description has been given for clearness of understanding only, and no unnecessary limitation should be understood therefrom, but the appended 110 claims should be construed as broadly as permissible in view of the prior art.

What we regard as new and desire to secure by Letters Patent is:

1. The combination of a steering-shaft 115 having its upper end provided with a reduced extension and a projecting threaded stud, a journal-collar mounted on said reduced extension and provided with a bolt-socket and with a circumferential groove, 120 a nut securing said journal-collar to said shaft, a steering-wheel having a spider provided with a cap-shaped hub mounted on said journal-collar and housing said nut, a pin in said hub engaging said circumferential groove, and a lock mounted in said spider and equipped with a bolt adapted to engage said socket.

2. The combination of a steering-shaft, 125 provided with a threaded extremity, a jour-

nal-collar fitted on said shaft, a nut securing said collar in position, a steering-wheel having a spider provided with a cap-shaped hub journaled on said journal-collar and housing said nut, means securing said hub rotatively on said journal-collar, a bolt-chamber and a lock-casing chamber formed integrally with said spider, a reciprocable

bolt mounted in the bolt-chamber, a lock-casing mounted in the lock-casing chamber, 10 and a key-actuated member mounted in said lock-casing and adapted to reciprocate said bolt.

MAURICE R. ROSEN.
RUDOLPH E. FISCHEL.
